UNITED STATES PATENT OFFICE.

HOWARD F. BROOKS, OF CHICAGO, ILLINOIS.

CHILD'S CARRIAGE.

SPECIFICATION forming part of Letters Patent No. 276,955, dated May 1, 1883.

Application filed October 28, 1882. (No model.)

To all whom it may concern:

Be it known that I, HOWARD F. BROOKS, a citizen of the United States of America, residing at Chicago, in the county of Cook and State of Illinois, have invented a new and useful Improvement in Folding Children's Carriages, of which the following is a specification, to wit:

My invention relates to children's carriages which may be folded into a small space for convenience of storage and transportation; and it consists in a jointed frame-work to which is suspended by springs a flexible bed or body, the frame adapted to be folded and stored entirely within the flexible bed, which incloses them with somewhat the appearance of a valise, and may be easily carried in the hand, substantially as hereinafter more fully set forth.

In order to enable others skilled in the art to which my invention relates to make and use the same, I will now proceed to describe its construction and operation, referring to the accompanying drawings, in which—

Figure 1 is a side elevation of my carriage. Fig. 2 is a perspective view of one of the wheels with the standard-sockets and part of the frame. Fig. 3 is a similar view of an end of one of the cross-pieces of the frame. Figs. 4 and 5 are views of the cross-pieces which connect the uprights of the frame with their sockets. Fig. 6 is a sectional view of one of the sockets. Fig. 7 is a perspective view of the flexible bed or body of the carriage with its suspending-springs. Fig. 8 is a similar view of the adjustable top with its supporting-frames. Fig. 9 is a sectional view of part of the same, showing the manner of constructing the top and jointing the frame. Fig. 10 is a section of the hinged joint in the wheel-frame, and Fig. 11 a view of the device used to hold the vehicle stationary and give it a springing vertical motion.

A represents a side-bar of the main frame, which is hinged in the center to enable it to be folded, as seen at a, and on the inside of this joint is a spring, a', Fig. 10, attached to one of the pieces, having a small hole through its outer end, which passes over a pin, a'', in the other piece when the parts are extended, and keeps them firmly in line. The bars A are, near each end, provided with or cast with a small frame or box, A', in which is journaled a small wheel, A'', and beyond this box A' the

bar A is turned upward and formed into a socket, A³, in the end of which is formed an L-shaped slot, the purposes of which will be presently understood. On the inside of the boxes or frames A' is cast a projection, B, formed with a tapered dovetailed groove, b, as seen in Fig. 2, and also a stud, b'. Two of these jointed bars A are placed parallel to each other at a suitable distance apart, and connected at each end by a cross-bar, B', on each end of which is a tapered dovetail tongue, b², which enters the corresponding grooves, b, in the offset B and wedges into place to hold the bars firmly together.

The sockets A³ are each provided with uprights or standards C C, having small pins or projections near their lower ends, which enter the L-shaped slot a³ of the socket, and when the standards are twisted firmly lock them in position. The upper ends of these standards are for a short distance turned somewhat smaller than the main part, forming a shoulder, c, below which, on one side, is a hook, c'. The two standards at the rear of the carriage are connected by a cross-bar or handle, C', to the ends of which are hinged long sockets C², which pass over the upper end of the standards C, resting on the shoulder c, and are secured in place by a spring-catch, c², on the standard, which engages with the socket, as clearly illustrated in Fig. 6. The two standards at the forward end of the carriage are connected by a similar cross-bar, C³, having short sockets C⁴, which engage with the standards, as just described, and the two bars C' C³, with their sockets, being interchangeable, the carriage may be pushed in either direction with equal facility.

D designates the bed or body of my carriage, which is made of carpet or other strong but flexible material, and is shaped somewhat like a boat, having its upper edges secured to a frame of jointed metal rods, or to a stiff rope, as may be desired. At each corner and in the center of each end the body D is provided with rings d, to which are secured springs D', of suitable size, and small chains D², which are engaged with the hooks c' on the standards C to suspend the bed or body, and to similar hooks on the handles or bars C' C³, which connect the standards at their upper ends.

- The seat is formed of a small piece of carpet, D^2 , or material similar to the body D , connected at its upper end to the suspending rings d at one end of the body, and at its lower end, by small chains d' , to the corresponding rings at the opposite end of the bed. These chains d' may be disengaged at any time to allow the lower end of the seat-piece D^2 to drop to the bottom of the bed, should it be desired to allow the child to recline at length. The sides of the bed or body are also provided at the center with suitable rings, d^2 , for the attachment of the usual strap, d^3 , to prevent the falling of the occupant.
- To support a top or cover for the carriage, I employ a metal rod or frame, E , having its lower ends slotted to pass easily over the screw-threaded studs b' on the wheel-boxes A' , and secured by a thumb-screw, e , so that it may be turned forward or back to shade the child from the sun. This frame is made in three or more pieces, as shown, screwed together, as seen at e' , Fig. 9, and it is supplied with a canopy, E' , composed of slats running longitudinally, and secured together by oil-cloth, canvas, or other flexible material, so that it may, when removed, be rolled up into a small space. This canopy E is provided with a series of rings, e^2 , which slide easily upon the jointed frame, and the end rings of this series are each furnished with a set-screw, e^3 . By this arrangement the canopy may be used on top of the frame, as represented in Fig. 1, or slid over one side of the same, as seen in Fig. 8, as may be required for the protection of the occupant.
- This device forms a convenient and cheap carriage, which gives the easiest motion obtainable, and when not required for use the whole may be taken apart readily and all the other parts stowed within the flexible bed D . The strap d^3 may then be secured to the rings d in the center of the ends of the body and used as a handle for carrying the device conveniently from place to place. The shortening of the suspension-chains at one end of the body by taking them up a link or two will lift that end of the bed, and it may thus be adjusted to the convenience of the occupant.
- Fig. 11 represents a spring-arm, S , secured at one end to a plate, S' , which rests upon the floor, and having its opposite end formed into an open box or trough, S^2 , supported by a spiral spring, s , resting on the plate. Two of these devices are employed, which are placed under one end of the carriage, with the wheels resting in the trough S^2 . This raises

the wheels off the floor and supports the carriage so it cannot move, and at the same time brings the connecting-bar between the two side bars, A , at a convenient height for the insertion of the foot beneath it, and the toe can then give the carriage a perpendicular springing motion, aided by the spring s , and serves admirably as a cradle.

Having thus fully described my invention, what I claim as new, and desire to secure by Letters Patent, is—

1. In a child's carriage, the wheels A^2 , inclosed within a box forming part of the side frame of the vehicle, substantially as described and shown.

2. In a folding child's carriage, the side bars, A , hinged together at their center, and provided at their ends with boxes A' , in which are journaled the supporting-wheels A^2 , and the sockets A^3 , in combination with the removable standards $C C$, to which the bed or body is suspended, substantially as shown and described.

3. In a folding child's carriage, the combination, with the hinged or jointed side bars, A , carrying the wheels A^2 , and formed with sockets A^3 , having L-shaped slots a^3 in their upper ends, of the standards $C C$, adapted to be locked by small projections engaging with said slots, and connected at their upper ends with cross-bars jointed or hinged to sockets fitting the upper ends of said standards, substantially as shown and described.

4. In a folding child's carriage, the frame E , constructed in several pieces, jointed together and pivoted to the carriage-frame, in combination with a canopy adapted to be rolled up and secured to the frame by a series of rings, so as to be moved from one side to the other and secured at any desired position, substantially as described and shown.

5. A folding child's carriage consisting, essentially, of the side bars, A , carrying the wheels A^2 , and having sockets A^3 , in which are secured the removable standards C , connected by cross-bars C' at their upper ends, the flexible bed or body D , and the adjustable top $E E'$, all constructed and arranged to operate substantially as and for the purpose set forth.

In testimony whereof I affix my signature in presence of two witnesses.

HOWARD F. BROOKS.
